UNITED STATES PATENT OFFICE

151,229

DESIGN FOR A SWIMMING FLIPPER

Donald F. Eddy, South Gate, Calif.

Application March 10, 1947, Serial No. 137,486

Term of patent 14 years

(Cl. D71—1)

To the Commissioner of Patents:

Be it known that I, Donald F. Eddy, a citizen of the United States, residing in South Gate, in the county of Los Angeles and State of California, have invented a new, original, and ornamental Design for a Swimming Flipper, of which the following is a specification, reference being had to the accompanying drawing, forming part thereof.

Fig. 1 is a top perspective view of a swimming flipper, showing my new design.

Fig. 2 is a bottom plan view thereof.

I claim:

The ornamental design for a swimming flipper, substantially as shown.

DONALD F. EDDY.
